UNITED STATES PATENT OFFICE.

MORGAN McCULLOUGH, OF LOS ANGELES, CALIFORNIA.

SUSPENDER-STRAP-FASTENING MEANS.

1,271,338.

Specification of Letters Patent.

Patented July 2, 1918.

Application filed December 27, 1917. Serial No. 209,161.

To all whom it may concern:

Be it known that I, MORGAN McCULLOUGH, a citizen of the United States, residing at Los Angeles, in the county of Los Angeles, State of California, have invented a new and useful Suspender-Strap-Fastening Means; and I do hereby declare the following to be a full, clear, and exact description of the invention, such as will enable others skilled in the art to which it appertains to make and use the same.

The present invention relates to a fastening means for securing crossing suspender straps or the like at their point of intersection, the object of the invention being to provide a fastening means of this character which embodies a novel combination of stitching and metallic fasteners, the stitching holding the superposed thicknesses together over a large area, while the metallic fasteners protect the stitching against any direct outward pull.

Further objects of the invention are to provide a suspender strap fastening means which will hold the intersecting straps tightly together and prevent them from being pulled apart, which is simple and inexpensive and will not add materially to the cost of manufacturing suspenders, and which will successfully withstand strenuous usage without tearing or becoming unfastened.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawings, in which:—

Figure 1 is a front elevation of a pair of intersecting suspender straps connected by fastening means embodying the invention.

Fig. 2 is a sectional view on the line 2—2 of Fig. 1.

Fig. 3 is a sectional view on the line 3—3 of Fig. 1.

Corresponding and like parts are referred to in the following description and indicated

in all the views of the drawings by the same reference characters.

Referring to the drawings, which illustrate one embodiment of the invention, the numerals 1 designate a pair of intersecting suspender straps which are provided at their lower ends with the usual button hole tabs 2. The two straps are superposed upon each other at their point of intersection, and headed metallic fastening members, such as the eyelets 3 penetrate the two thicknesses of material at points adjacent the corners of the intersection. Lines of stitching 4 extend along opposite sides of the intersection, being parallel thereto and disposed within an inner area defined by the eyelets 2. At the corners of the intersection the ends of these lines 4 of stitching are connected by curved lines of stitching 5 which extend around the inner sides of the respective eyelets 3. It will thus be seen that the lines 4 and 5 of stitching constitute a continuous line of stitching which holds the suspender straps together, although it is disposed in such a manner as to be protected by the eyelets 3, thereby shielding the stitching from any direct outward pull such as would tear it apart. Arranged within this outer line of stitching there may be an inner line of stitching 6 for holding the two thicknesses of material closely together at the center of the intersecting area. Both lines of stitching, however, are within the area defined by the eyelets 3 so as to be protected thereby against any direct upward pull. The two suspender straps are thus securely fastened together, being held in intimate contact with each other over a large area by the stitching, and the stitching being protected against direct outward pull such as would tear it apart by the eyelets. Suspenders manufactured in this manner will successfully withstand the most strenuous usage without tearing or pulling apart at the intersection of the straps.

Having thus described the invention, what I claim as new and desire to secure by Letters Patent, is:—

The combination of a pair of intersecting suspender straps, with means for fastening said straps at their crossing point, said fastening means comprising headed me-

metallic fasteners which penetrate the two straps at the corners where they cross each other, and lines of stitching arranged within the area defined by the metallic fasteners whereby the said metallic fasteners will protect the lines of stitching against direct outward pull.

Copies of this patent may be obtained for five cents each, by addressing the "Commissioner of Patents, Washington, D. C."

In testimony whereof I have signed my name to this specification in the presence of two subscribing witnesses.

MORGAN McCULLOUGH.
